FEEDING MECHANISM FOR SEWING-MACHINES.

946,662.

Specification of Letters Patent. Patented Jan. 18, 1910.

Application filed May 18, 1909. Serial No. 496,803.

To all whom it may concern:

Be it known that I, ALBERT H. DE VOE, a citizen of the United States, residing at Elizabeth, in the county of Union and State of New Jersey, have invented certain new and useful Improvements in Feeding Mechanism for Sewing-Machines, of which the following is a specification, reference being had therein to the accompanying drawings.

This invention has for its object to provide differential feeding mechanism for use particularly in gathering or Shirring fabrics, which shall be effective in operation and conveniently adjusted for use in different classes of work.

In its preferred embodiment, the mechanism comprises a primary feed-bar and a work-engaging member fixed thereon, the feed-bar being pivotally connected with the usual upright arms upon the feed-rock-shaft disposed at the rear side of the machine parallel with the main-shaft to which it is connected by means of a crank-arm and yoked link-bar embracing an actuating eccentric upon the main-shaft and provided with a roller-stud moving in a run-way of a feed regulating lever pivotally mounted upon the front of the machine where it is readily accessible to the operator. Slidingly mounted upon the primary feed-bar is the secondary feed-bar carrying an independent work-engaging member and connected by means of a pitman with a crank-arm at one end of the secondary feed rock-shaft disposed at the front of the machine parallel with the main-shaft and having a second slotted crank-arm to which is adjustably connected the forward end of a link whose rearward end is pivotally connected with a crank-arm upon the primary feed rock-shaft from which the secondary feed rock-shaft thus derives its operative movements. Opposed to the differentially moving primary and secondary feeding members is a three-part presser-foot, of which the relatively yielding forward and rearward parts are opposed to said feeding members, respectively, an intermediate relatively yielding portion being adapted at certain times to rest upon the work-plate intermediate said feeding members to insure the detention of the fulled material thrust under the presser-foot by the secondary feed-dog for the stitching operation.

The present invention includes certain details of construction which will be herein-

after described and pointed out in the appended claims.

In the accompanying drawings Figure 1 is a front side elevation of a sewing machine embodying the present improvements, and Fig. 2 a plan of the same with the bracket-arm and work-plate removed. Fig. 3 is a perspective view of the feeding mechanism detached. Fig. 4 is a perspective view of a portion of the feeding mechanism and the compound presser-foot. Fig. 5 is a perspective view of the presser-foot detached and Fig. 6 a sectional elevation of the same.

The machine frame comprises the base 1 from which rises the upright portion 2 of the bracket-arm with overhanging portion 3 in the head 4 of which is journaled the reciprocating needle-bar 5 carrying the needles 6 mounted in the twin needle-clamp 7. The needle-bar is provided with the usual collar 8 connected by means of the link 9 with the crank-arm 10 near the forward end of the needle actuating rock-shaft 11 provided at its rearward end with the crank-arm 12 connected by means of the eccentric-rod 13 with the actuating eccentric upon the main-shaft 14. Coöoperating with the needles 6 are the two rotary single-chain-stitch loopers 15, one being mounted upon the main-shaft 14 and the other upon a short shaft 16 connected by gears 17 and 18 with the intermediate shaft 19 which is in turn connected by means of the intermeshing gears 20 and 21 with the main-shaft; whereby the loopers 15 are caused to rotate in unison.

The primary feed-dog 22 is fixed upon a separate member 23^a of the primary feed-bar 23 which is pivotally mounted by means of the pin 24 between the upright arms 25 of the feed-rock-shaft 26 which is provided with a depending crank-arm 27 carrying a stud 28 embraced by the rearward end of the link-bar 29 provided intermediate its ends with the yoke 30 and at its forward end with a roller-stud 31 entering the run-way 32 in the hub portion 33 of the feed regulating lever 34 which is fulcrumed, by means of the pin 35, in a bracket-piece 36 extending from the base 1 at the front side of the machine. The lever 34 is formed with a segmental slot 37 concentric with its fulcrum-pin 35, said slot being entered by a stud 38 projecting from the bracket-piece 36 and provided with a clamp-nut 39 by which the lever 34 may be secured in position. The main-shaft 100

105

110

14 has fixed thereon the feed-actuating eccentric 40 embraced by the slide-block 41 provided upon opposite sides with slide-ways which are entered between the parallel members of the yoke 30. Although the actuating member 40 is shown in the drawings of circular form and is herein specifically termed an "eccentric", it is evident that its function is merely that of the cam, such particular form being adopted therefor as may best suit its purpose in the performance of the work for which the machine is designed.

10 The primary feed-bar 23 is provided with a forwardly projecting yoke 42 which embraces the feed-lifting cam or eccentric 43 fixed upon the main-shaft.

15 The primary feed-bar section 23a is formed in one face with a longitudinal channel within which is slidably fitted the reduced adjacent end portion of the secondary feed-bar 44 to whose forward end is adjustably secured, by means of the fastening screw 45 entering the vertical slot 46 in the feed-bar, the shank 47 of the secondary feed-dog 48 having its several feeding surfaces disposed in substantial alinement with those of the primary feed-dog 22. The rearward end of the secondary feed-bar 44 is provided with a lateral stud-screw 49 embraced by one end 30 of the bent link 50 whose opposite end embraces the stud-screw 51 carried by the upright crank-arm 52 at one end of the secondary feed rock-shaft 53 having fixed upon its opposite end the upright crank-arm 54 formed with the slot 55.

20 The primary feed rock-shaft 26 is provided with an upwardly extending crank-arm 56 carrying a stud-screw 57 embraced by the rearward end of the curved link 58 whose forward end is provided with the flanged bushing 59 entered by the bolt 60 having the head 61 and adjacent flattened shank 62 fitted within the slot 55 of the crank-arm 54, the parts being secured together in a manner well known by means of the nut 63 applied to the reduced threaded end portion of the bolt 60. By the means just described it will be observed that the secondary feed-dog derives its operative movements through adjustable connections with the primary feed rock-shaft, whereby a single adjustment of the feed regulating lever 34 causes a proportionate adjustment of the operative movements of the primary and secondary feed-dogs, while the adjustment of the connecting link 58 with the slotted crank-arm 54 produces a relative adjustment between the operative movements of the two feed-dogs.

25 In the head 4 of the bracket-arm is journaled the usual presser-bar 64 embraced by the presser-spring 65 by which it is normally pressed downwardly. The reduced lower end of the presser-bar 64 enters the usual socket 66 of the presser-foot shank 67 formed with a laterally extending foot-plate 68 hav-

ing a downwardly offset forward or toe-portion 69 with upturned forward extremity, the toe portion being disposed immediately above the secondary feed-dog 48 which, with the primary feed-dog, is adapted to rise through the usual feed-dog apertures in the work-plate 70 beneath which the feed-actuating mechanism is disposed.

30 Within the bottom recess of the foot-plate 68, and immediately above the primary feed-dog 22, is disposed the yielding heel-plate 71 from the upper face of which projects the cylindrical post 72 through suitable apertures in the feed-plate 68 and a bearing lug 73 extending forwardly from the upper end of the shank 67. The heel-plate 71 is provided with a steady-pin 74 entering an aperture in the lower part of the shank 67, and interposed between the top of the heel-plate and the upper ends of suitable sockets in the feed-plate are springs 75 tending to press the heel-plate downwardly into a position substantially flush with the toe portion of the foot in which position it is normally held by means of the stop-collar 76 secured to the upper end of the post above the bearing lug 73 by means of the transverse pin 77.

35 Disposed within the recess in the lower face of the foot-plate 68, and in advance of the heel-plate 71, is the auxiliary pressure or detaining member 78 with upwardly and rearwardly inclined lower or operative face. This intermediate member is provided with a shank 79 secured by means of fastening screws 80 upon a block 81 centrally apertured to fit the post 72 intermediate the foot-plate 68 and bearing lug 73, a spring 82 being interposed between the said bearing lug and the top of the block 81 to force the lower end of the latter downwardly upon a seat 83 afforded therefor upon the top of the foot-plate 68. The shank 79 is so offset laterally adjacent the member 78 that it is adapted to be engaged by the top of the heel-plate 71 when the latter rises sufficiently to take up the clearance which is normally provided between such parts. The pressure member 78 is so disposed in relation to the differentially moving feed-dogs that in the initial rising movement of the main or primary feed-dog it forms a relatively yielding continuation of the heel-plate, being arranged directly above such feed-dog, but as the feeding members advance for moving the work a stitch length, the main feed-dog recedes from beneath the pressure member 78 which latter is permitted to drop toward the work-plate just in advance of the position which the adjacent end of the secondary feed-dog assumes at the end of the feeding movement of the latter. As will be observed, the operative edge of the pressure member 78 adjacent the rearward end of the toe portion 69 serves, with the feeding men-

bers beneath the work-plate, to nip the gathered material just deposited beneath the same by the secondary feed-dog until the descent of the needles through the work to secure such portion of material in position, the succeeding rise and operative or advancing movement of the main feed-dog serving in conjunction with the intermediate pressure-member 78 and toe plate 69 to advance 10 the stitched and ruffled material to make room for the succeeding gathered portion from the auxiliary feed-dog 48. As the pressure member 78 is permitted to descend below the heel-plate 71 after the initial feeding movement of the primary feeding member 22, it will be observed that its front edge affords an abutment rearward of the needle apertures 88 against which the folds or crimps of fabric are thrust by the auxiliary feeding member 48, in the crowns of which the needles descend, thereby dividing them each into two small crimps which are confined in position by the adjacent stitches.

The rearward end of the toe-plate 69 is formed with a series of longitudinal slots 84, in which are disposed a corresponding series of serrated detent blades 85 fixed upon a rocking pin 86 which is seated in a transverse groove in the upper face of the toe-plate 69 and held in place by means of a flat spring 87 whose free end presses upon the top of the central detent blade, whereby said blades are pressed normally downward so as to extend beneath the lower operative face of the toe-plate 69. These detent blades, which embrace the needle apertures 88 and extend both forwardly and rearwardly of the same when pressed upwardly in opposition to the spring 87 in their operation upon the fabric, serve to engage the fulled fabric propelled by the auxiliary feed-dog and to prevent the disarrangement of the folds or crimps by maintaining a slight pressure upon the same against the work-plate intermediate the feed-dog apertures when the feed-bar descends after each work advancing movement.

In the machine shown in the drawings, in which the looper mechanism occupies almost the entire space beneath the work-plate adjacent the line of feed, it is impracticable to make use of such actuating connections intermediate the primary and secondary feeding devices as have been employed heretofore at the outer end of the machine, and the connection 58 has therefore been disposed in the present machine intermediate the stitch-forming mechanism and the rear end of the machine where the needle-actuating eccentric carried by the main-shaft is located. In addition to the advantage thus gained of locating this connection where there is ample room for its operation combined with the necessary range of adjustment, the point of adjustment is brought

close to the primary feed-regulating lever 34, so that both adjustments are closely associated together at a very favorable position for manipulation by the operator.

Having thus set forth the nature of the invention what I claim herein is:—

1. In a sewing machine, the combination with the main-shaft provided with a needle-actuating member, the work-plate and stitch-forming mechanism comprising a reciprocating needle-bar carrying a needle and an operative connection intermediate said needle-bar and the needle-actuating member of the main-shaft, of a primary feeding mechanism comprising a feeding member and an actuating rock-shaft disposed below and extending longitudinally of the work-plate, a secondary feeding mechanism comprising a feeding member disposed upon the same side of the work-plate as that of the primary feeding mechanism and an actuating rock-shaft therefor also disposed below and extending longitudinally of the work-plate, means for actuating the first-named rock-shaft, an adjustable connection between the said rock-shafts and arranged intermediate the stitch-forming mechanism and the needle-actuating member of the main-shaft, and means for imparting simultaneous rising and falling movements to said feeding members.

2. In a sewing machine, the combination with the frame comprising the base and overhanging bracket-arm rising therefrom, the work-plate mounted upon said base, the main-shaft journaled beneath and extending longitudinally of the work-plate, and stitch-forming mechanism, of a primary feeding mechanism comprising a feed-bar, a feeding member fixed thereon, an actuating rock-shaft disposed below the work-plate parallel with the main-shaft and provided intermediate said feed-bar and the base of the bracket-arm with a crank-arm, a secondary feeding mechanism comprising a feed-bar slidingly fitted upon the first-named feed-bar, a feeding member mounted thereon, an actuating rock-shaft parallel with the first-named rock-shaft and provided upon opposite ends with upwardly extending crank-arms, a link connection intermediate one of the crank-arms of the secondary actuating rock-shaft and the secondary feed-bar, a connection intermediate the crank-arm of the first-named actuating rock-shaft and the second crank-arm of the secondary actuating rock-shaft, means connected with the main-shaft for actuating the first-named rock-shaft, and means for imparting rising and falling movements to the primary feed-bar.

3. In a sewing machine, the combination with primary and secondary feeding members, primary and secondary rock-shafts disposed respectively at the rear and front of

4. the machine with which said feeding members are respectively connected, actuating means for the primary rock-shaft including a cam and a forwardly projecting yoked vibratory link-bar with means disposed at the front of the machine for varying the path of movement of said link-bar, crank-arms upon said rock-shafts, and a link connection intermediate said crank-arms and 10 adjustable upon the crank-arm of the secondary rock-shaft.
5. In a sewing machine, the combination with the work-plate, stitch forming mechanism and differential feeding mechanism comprising two relatively movable feed-dogs and means for imparting operative movements thereto, of a presser-foot comprising a plurality of relatively yielding parts of which a toe-plate and heel-plate 15 are disposed each above one of said relatively movable feed-dogs, and an intermediate part is adapted to rest upon the work-plate between the paths of operative movement of said feed-dogs.
10. In a sewing machine, the combination with the work-plate, stitch forming mechanism and differential feeding mechanism comprising two relatively movable feed-dogs and means for imparting operative 20 movements thereto, of a presser-foot comprising a plurality of relatively yielding parts of which a toe-plate and heel-plate are disposed each above one of said relatively movable feed-dogs, and an intermediate part 25 is adapted to rest upon the work-plate intermediate the paths of operative movement of said feed-dogs, said toe-plate being provided at its rearward end with spring-pressed detent-blades normally extending below its operative face, and adapted to 30 engage the fabric advanced by the feeding member beneath the same.
15. In a sewing machine, the combination with the work-plate, stitch forming mechanism and differential feeding mechanism comprising two relatively movable feed-dogs and means for imparting operative movements thereto, of a presser-foot comprising a plurality of relatively yielding parts of which a toe-plate and heel-plate are disposed each above one of said relatively movable feed-dogs, and an intermediate part 35 is adapted to rest upon the work-plate intermediate the paths of operative movement of said feed-dogs, said toe-plate being provided at its rearward end with spring-pressed detent-blades normally extending below its operative face, and adapted to 40 engage the fabric advanced by the feeding member beneath the same.
20. In a sewing machine, the combination with the work-plate, stitch forming mechanism and differential feeding mechanism comprising two relatively movable feed-dogs and means for imparting operative movements thereto, of a presser-foot comprising a plurality of relatively yielding parts of which a toe-plate and heel-plate are disposed each above one of said relatively movable feed-dogs, and an intermediate part 45 is adapted to rest upon the work-plate intermediate the paths of operative movement of said feed-dogs, said toe-plate being provided at its rearward end with spring-pressed detent-blades normally extending below its operative face, and adapted to 50 engage the fabric advanced by the feeding member beneath the same.
25. In a sewing machine, the combination with the work-plate, stitch forming mechanism and differential feeding mechanism comprising two relatively movable feed-dogs and means for imparting operative movements thereto, of a presser-foot comprising a plurality of relatively yielding parts of which a toe-plate and heel-plate are disposed each above one of said relatively movable feed-dogs, and an intermediate part 55 is adapted to rest upon the work-plate intermediate the paths of operative movement of said feed-dogs, said toe-plate being provided at its rearward end with spring-pressed detent-blades normally extending below its operative face, and adapted to 60 engage the fabric advanced by the feeding member beneath the same.
30. In a sewing machine, the combination with the work-plate, stitch forming mechanism and differential feeding mechanism comprising two relatively movable feed-dogs and means for imparting operative movements thereto, of a presser-foot comprising a plurality of relatively yielding parts of which a toe-plate and heel-plate are disposed each above one of said relatively movable feed-dogs, and an intermediate part 65 is adapted to rest upon the work-plate intermediate the paths of operative movement of said feed-dogs, said toe-plate being provided at its rearward end with spring-pressed detent-blades normally extending below its operative face, and adapted to 70 engage the fabric advanced by the feeding member beneath the same.
35. In a sewing machine, the combination with the work-plate, stitch forming mechanism and differential feeding mechanism comprising two relatively movable feed-dogs and means for imparting operative movements thereto, of a presser-foot comprising a plurality of relatively yielding parts of which a toe-plate and heel-plate are disposed each above one of said relatively movable feed-dogs, and an intermediate part 80 is adapted to rest upon the work-plate intermediate the paths of operative movement of said feed-dogs, said toe-plate being provided at its rearward end with spring-pressed detent-blades normally extending below its operative face, and adapted to 85 engage the fabric advanced by the feeding member beneath the same.

In testimony whereof, I have signed my name to this specification, in the presence of two subscribing witnesses.
